UNITED STATES PATENT OFFICE.

FRANK M. PIERCE, OF CHICAGO, ILLINOIS, ASSIGNOR TO PIERCE WRAPPING MACHINE COMPANY, OF CHICAGO, ILLINOIS, A CORPORATION OF ILLINOIS.

DOUBLE-WRAPPER /WRAPPING-MACHINE.

1,263,924.

Specification of Letters Patent. Patented Apr. 23, 1918.

Application filed November 26, 1915. Serial No. 63,502.

To all whom it may concern:

Be it known that I, FRANK M. PIERCE, a citizen of the United States, and a resident of the city of Chicago, in the county of Cook and State of Illinois, have invented certain new and useful Improvements in Double-Wrapper Wrapping-Machines; and I do hereby declare that the following is a full, clear, and exact description of the same, reference being had to the accompanying drawings, and to the numerals of reference marked thereon, which form a part of this specification.

This invention relates to an improved type of wrapping machine adapted to apply a plurality of wrappers on annular shaped bodies. In most of the types of wrapping machines heretofore designed, the wrapper has been applied upon the article by a revolving shuttle generally having a removable section to permit insertion of the article to be wrapped through the eye of the shuttle, after which the section is replaced for the wrapping operation. However, in this invention the shuttle is provided with a normally open gap to permit insertion into or removal of articles from the shuttle without necessitating adjustment of the parts of the shuttle, and the shuttle is so mounted and driven as to apply one or more wrappers on the article by merely imparting a simple revolving movement thereto.

It is an object therefore of this invention to construct a wrapping machine capable of applying one or more wrappers upon an article and permitting insertion and removal of the article into and from the machine without requiring adjustment of the wrapper applying means.

It is also an object of this invention to construct a wrapping machine adapted to support, advance, and revolve an annular article through the eye of an open gap shuttle which is also revolved by suitable mechanisms and carries a plurality of reels of wrapping material for application upon the article, rotating therearound as the article is revolved therethrough.

It is also an object of this invention to construct a wrapping machine adapted to support annular articles in upright position during a wrapping operation, and provided with an improved adjusting means to permit adjustment of different sized articles to centralize the same in the wrapping shuttle.

It is also an object of this invention to construct a wrapping machine provided with an open gap shuttle with a series of rollers mounted on an open gap circular guide to receive the shuttle fitted closely thereover to support the same rotatably thereon, permitting the shuttle to be rotated for application of a wrapper upon an article without necessitating closure of the gap in the shuttle for the purpose.

It is furthermore an important object of this invention to construct a wrapping machine capable of applying one or more wrappers upon an annular article by means of an open gap shuttle adapted to be revolved around the article as the article is moved therethrough, and with means conveniently accessible at the top of the machine for self-adjusting the support for the article, for articles of different size to secure proper alinement thereof through the eye of the shuttle.

It is finally an object of this invention to construct an improved type of double wrapper wrapping machine capable of operating at high speed upon articles of different size, permitting insertion and removal of the article into and from the machine without necessitating adjustment of the wrapper carrying shuttle and provided with clutch controlled driving mechanism associated with a brake whereby when the drive is disconnected from the machine the brake is applied to stop the movement of the parts.

The invention (in a preferred form) is illustrated in the drawings and hereinafter more fully described.

In the drawings:

Figure 1 is a front elevation of a machine embodying the principles of my invention.

Fig. 2 is a side elevation of the machine. Fig. 3 is a central vertical section therethrough with parts in elevation.

Fig. 4 is a top plan view of the wrapping machine.

Fig. 5 is a fragmentary section taken on line 5—5 of Fig. 1.

Fig. 6 is a fragmentary section taken on line 6—6 of Fig. 5.

Fig. 7 is a detail sectional view taken through the shuttle showing a portion of the frame on line 7—7 of Fig. 2.

Fig. 8 is a fragmentary sectional detail illustrating adjusting means for the lower guide rollers.

Fig. 9 is a detail view illustrating the brake for the machine.

Fig. 10 is a detail view illustrating the tension take-up means for the adjusting chains.

Fig. 11 is a detail of one of the wrapper carrying spindles of the shuttle.

Fig. 12 is a fragmentary elevation of the shuttle showing the wrapping reels and folding devices thereon.

Fig. 13 is a side view of the shuttle.

Fig. 14 is a sectional detail of the shuttle illustrating one of the folding devices.

Fig. 15 is an end view of the folder with a part thereof broken away.

As shown in the drawings:

The frame of the machine embraces two similarly constructed side frame members 1 and 2, respectively, which are integrally or otherwise rigidly connected one to another at their upper ends by an arched cross frame member 3, and a lower cross frame member 4, which is rigidly bolted to said side frame members 1 and 2. A stay rod or bar 5, is also rigidly secured between said side frame members 1 and 2, at the lower end thereof, at the front of the machine. Bolted on the rear surface of the side frame member 1, is an upwardly curved extension bracket 6, affording a bearing at its upper end for a drive shaft 7, which also extends through bearings 8 and 9, provided on the inner surface of said side frame member, as clearly shown in detail in Fig. 3. A large driving pulley 10, is mounted upon said shaft and associated therewith is a clutch member 11, whereby said pulley may be connected with the shaft to drive the same.

For the purpose of actuating said clutch, a long lever 12, is pivoted in a bracket 13, secured on the rear surface of said side frame member 1, which is connected to a short lever 14, which is in turn connected to said clutch 11, to engage or disengage the same with said wheel 10, as the case may be. The outer end of said lever 12, extends beneath a vertically mounted retaining bar 15, secured on the outer surface of said side frame mem-

ber 1, to limit the movement of said lever 12. Mounted on the inner surface of each of the side frame members 1 and 2, are upper and lower brackets, denoted respectively by the reference numerals 16 and 17, in which are secured upright guide rods 18. A traveling carriage 19, is provided, consisting of side frame members having extensions 20 and 21, respectively, which fit slidably upon said upright rods 18, and journaled in said carriage are a pair of shafts on which supporting and driving rollers 22 and 23, are mounted, the surfaces thereof, as clearly shown in Figs. 1 and 5, corrugated to insure positive contact with an annular article such as a tire 24, supported thereon for wrapping, as shown in Fig. 1.

For the purpose of insuring simultaneous rotation of said rollers 22 and 23, in the same direction, sprocket wheels are secured on the outer ends of said shafts on which said rollers are mounted, and a chain 24, is trained thereover. For the purpose of imparting a drive to said rollers 22 and 23, a shaft 25, is mounted vertically in bearings for the purpose on the inner surface of the side frame member 1, and at its upper end is provided with a worm wheel 26, meshing with a worm 27, secured on the drive shaft 7. At one side of the traveling carriage an extension 28, is formed, through which said vertical shaft 25, extends, and above which a bevel pinion 29, is feathered on said shaft, which meshes with a bevel pinion 30, secured upon the same shaft with the roller 23. One side of each of said upright guide rods 18, is provided with a series of teeth, as clearly shown in Fig. 6, and mounted in the carriage 19, is a horizontal shaft 31, the ends of which extend through the lower members 21, and are each cut to form small pinions 32, to mesh with the teeth cut on said guide rods, so that when the shaft 31, is rotated the carriage 19, is raised or lowered thereby. For the purpose of rotating said shaft 31, one end thereof is extended, as clearly shown in Fig. 6, and is provided with a sprocket wheel 33, about which a chain 34, is trained, with one end of said chain, as clearly shown in Figs. 2, 3, and 10, secured on the hub of a disk 35, journaled on a stud on the frame member 1, and the other end of said chain 34, trained about a pinion 36, and secured on the hub of another disk 37, journaled on another stud on said frame member 1. Each of said disks 35 and 37, have one end of spiral springs 38 and 39, respectively, connected thereto, the other ends of the springs being connected upon the stud on which the disk is journaled, in such a manner as to rotate said disks in opposite directions. Consequently with movement of said chain 34, as the pinion 38, moves toward or away from the pin-

ion 36, with adjusting movements of the carriage 19, the slack in said spring 34, is taken up. Said pinion 36, is secured upon the end of a short shaft journaled in a bearing provided in one of the upper brackets 16, and the other end of said shaft, as clearly shown in Fig. 4, is cut to form a small worm pinion 40, meshing with a worm 41, on the lower end of an inclined shaft 42, which is mounted in bearings on said frame member 1, and at its upper end is provided with an actuating handle 43.

Mounted on said carriage 19, are a pair of brackets 44, which are slidable toward and away from one another, each having journaled at its upper outer end inclined guide rollers 45, which bear against the sides of the tire or other article being wrapped. For the purpose of adjusting said brackets 20 and said rollers therewith, a double lead screw 46, is journaled in said carriage 19, and each of said brackets 44, is provided with extensions 47, which are internally threaded and through which said lead screw 25 extends and engages therewith. Said lead screw at one of its ends is extended and provided with a sprocket wheel about which a chain 48, is trained, and said chain is also trained about a sprocket wheel secured to a hand wheel 49, which is manually actuatable to thereby rotate said lead screw 46, and adjust said guide rollers 45, toward or away from one another, as the case may be.

Formed on or secured beneath the arched cross frame member 3, is a depending crescent shaped frame 50, shown in dotted lines in Fig. 7, on the forward surface of which is secured in close relation a number of rollers 51. Rotatably mounted upon said rollers 51, is an open gap circular shuttle 52, which, as clearly shown in the sectional view in Fig. 3, is provided with a groove on its inner periphery which fits over said rollers 51, to maintain the shuttle associated therewith. Means is provided for driving said shuttle 52, and for this purpose a driving pulley 53, is secured upon said drive shaft 7, at one side of said shuttle, and an idler pulley 54, of similar size and construction 50 is mounted on a short shaft in bearings 55, secured on the inner surface of the frame member 2, and as clearly shown in Fig. 1, smaller idler pulleys 56 and 57, are mounted on the upper end of the machine, permitting 55 a driving belt 58, to be trained about all of said pulleys and around the upper outer periphery of the shuttle. In order to maintain the requisite tension upon said belt 58, said idler pulley 57, is adjustably mounted 60 on the end of a lever 59, pivoted at its middle on the cross frame member 3, and at its other end loosely engaging on an upright rod 60, with a spiral compression spring 61,

bearing on said end of said lever and also beneath an adjustable wing nut 62, so that 65 said pulley 57, is normally thrust upwardly beneath the belt trained therearound.

Journalized on the front surface of said shuttle 52, are spindle or wrapper carrying reels 63 and 64, respectively, the one for paper and the other preferably for burlap, as in wrapping coils of wire, although of course the same or different material for wrapping may be used upon said reels. Adjacent the reel 63, is a tension and folding device 75 mounted on a plate 65, having a plurality of pins 66, arranged in staggered relation thereon around which the wrapping material, denoted by the reference numeral 67, is trained, and thence through a pivoted 80 tapered double folding or creasing device 68, which folds both edges of the material being led to the article being wrapped. The folder device 68, as clearly shown in Figs. 1 and 12 to 15, consists of one tapered plate 85 having another plate 68a, riveted thereto and spaced therefrom and bent over the edges of said tapered plate so as to fold the opposite edges of a strip of material drawn there-through, and a stop pin 67a, is provided to 90 limit the outward swing of said device. Similarly mounted adjacent the reel 64, is another tension device comprising a plate 69, having a plurality of pins 70, projecting therefrom around which the wrapping material, denoted by the reference numeral 71, is trained, and thence around a tapered guide roller 72, to the article being wrapped.

For the purpose of maintaining the article being wrapped properly centralized 100 through the eye of the shuttle 52, guiding means is provided comprising three rollers 73, arranged in the angled relation shown in Fig. 1, all pivoted on one end of a lever 74, which, at its other end, is pivoted upon 105 a rearwardly extending bracket 75, secured to the arched cross frame member 3. Formed integrally on said lever 74, on each side thereof, are upwardly extending plates 76, which extend on each side of the bracket 75, 110 thereby guiding said lever 74, in its pivotal movement, and a pin 77, is secured between said upright plates 76, to limit the downward movement of said lever 74.

As clearly shown in Figs. 2 and 3, the upper edge of the rear end of said lever 74, is provided with a series of notches and a weight 78, provided with a pin 79, secured in extensions thereof, is adapted to be suspended on said lever with said pin seating 115 in said notches to permit adjustment of said weight at different points on said lever, said weight having a forward extension 80, which bears upwardly beneath the under surface of said lever to brace the weight in its attached position on the lever.

In order to bring the machine to rest immediately after disengagement of the clutch 11, by the lever 12, a brake is provided comprising a brake drum 81, formed on the rear surface of the pulley 53, and disposed to bear against the under side thereof is a brake shoe 82, shown in detail in Fig. 9, mounted on the end of a pivoted lever 83, which is mounted on said side frame member 1. The other end of said lever 83, bears upon a compression spring 84, which normally acts to maintain the brake shoe 82, away from the brake drum 81, but the position of said lever 83, is such that when the clutch releasing lever 12, is thrown down to release the clutch 11, said lever 12, contacts the end of said lever 83, depressing the same against the compression of its spring 84, and applying the brake shoe on the brake drum. The operation is as follows:

The article to be wrapped, shown in Fig. 1, and denoted by the character X, is placed into the machine resting upon the rollers 22 and 23, and projecting through the eye of the shuttle 52, which first of course must be rotated into a position to dispose the gap therein at the lower portion thereof to permit passage of the article therethrough. The wrapping material from the respective reels 63 and 64, is then attached on the article by making a few turns thereon or by adhesive or other suitable means, and the lever 12, then moved upwardly to engage the clutch 11, with the driving pulley 10, whereby the drive shaft 7, is caused to rotate. The pulley 53, on said drive shaft around which the belt 69, is trained, serves to revolve the shuttle 52, at a high rate of speed and the rollers 22 and 23, also receiving their drive from said shaft 7, through the vertical shaft 25, serve to revolve the article X, so that as the wrapper is wound therearound the article of course is moved to revolve and receive a wrapper extending entirely therearound. The lever 12, is then thrown downwardly, thus disengaging the clutch 11, and causing application of the brake shoe 82, upon the brake drum 81, to stop the machine in a short space of time.

Of course articles of different size require the parts of the machine to be adjusted to secure proper alinement and centralizing of the article through the eye of the shuttle, and for this purpose the handle 43, is rotated, thus through the proper gearing connected therewith, actuating the chain 34, which turns the shaft 31, causing the carriage 19, on which the supporting rollers 22 and 23, are mounted, to move upwardly or downwardly, as the case may be, upon the upright guide rods 18. The upper guide rollers 73, bear gravitationally upon the ar-

ticle being wrapped, and the pressure with which the same bear upon the article is determined by the position of the weight 78, which is adjustable upon the pivoted lever 74, on which said rollers 73, are mounted. The slight change in the length of the periphery of the shuttle over which the driving belt 69, tracks when the gap is in an upper position as said shuttle rotates, is compensated for by the adjustable idler pulley 57, mounted on the end of the lever 59, which is spring impelled and acts as a tension means for said belt. The lower guide rollers 45, are of course adjustable toward and away from one another for articles of different width merely by actuating the hand wheel 49, which is connected by suitable gearing to the lead screw 46, which actuates the brackets for said rollers on said carriage 19.

I am aware that various details of construction may be varied through a wide range without departing from the principles of this invention, and I therefore do not purpose limiting the patent granted otherwise than necessitated by the prior art.

I claim as my invention:

1. A wrapping machine of the class described comprising a frame, an adjustable carriage mounted therein, power driven supporting rollers for an article mounted in said carriage, means for adjusting said carriage, a chain and sprocket for operating said means, a plurality of alining rollers carried on said carriage, means for adjusting the same across the face of the supporting roller and mechanism for applying a wrapper upon the article.

2. In a wrapping machine a rotatable shuttle, a vertically adjustable carriage, supporting rollers thereon, mechanism for adjusting the carriage vertically, spring impelled independently operating means for taking up the slack in said mechanism and sets of alining rollers, one set acting on the top and sides of the article and the other set acting on the sides of the article adjacent the supporting rollers.

3. In a wrapping machine an adjustable carriage, means for adjusting the carriage, a chain for actuating said means to adjust the carriage, disks connected with each end of the chain, a spring for automatically rotating each of said disks to take up the chain when the carriage is adjusted, rotatable supporting rollers on said carriage, adjustable guide rollers on the carriage and an open shuttle adapted to apply a plurality of wrapping to an article.

4. In a wrapping machine an adjustable carriage, supporting and guiding rollers thereon adjustable together and independently of each other, a swinging lever, guide

arms secured thereto, a plurality of rollers on the inner end of said lever, an adjustable weight on said lever to press the rollers in firm engagement with the article wrapped 5 and a shuttle acting to wrap the article.

5. In a machine of the class described a frame, upright guide rods mounted in the lower end thereof, a vertically adjustable carriage mounted on said guide rods, a shaft 10 journaled through said carriage, teeth formed on the end of said shaft and on said guide rods to intermesh with one another to cause movement upwardly and downwardly of said carriage when said shaft is rotated, rollers journaled in said carriage to support 15 an article to be wrapped, means imparting a drive thereto in the same direction of rotation, a vertically mounted revoluble shuttle having an open gap therein mounted at the 20 upper portion of said machine adapted to receive the article to be wrapped engaged

through the eye thereof, and a plurality of means on said shuttle to receive wrapping material to apply a double wrapper upon the article.

25

6. A wrapping machine comprising rollers for supporting and advancing an article to be wrapped, a revoluble shuttle, means thereon for folding both edges of a paper wrapping and winding the same around the 30 article to be wrapped and means on said shuttle for simultaneously winding a fabric wrapping on the article over the paper wrapping.

In testimony whereof I have hereunto 35 subscribed my name in the presence of two subscribing witnesses.

FRANK M. PIERCE.
